KEY TAG AND DIRECTORY

Application filed September 26, 1929. Serial No. 395,226.

This invention relates to a tag for keys, and more particularly a hotel key identification tag combined with or forming in itself a multi-purpose device such as a directory or guide that will be useful to the hotel guest when in possession of the tag with his key. While features of this invention may be useful for other purposes, the particular form hereinafter shown and described aims to provide in a unit a key identification or protection tag plus a shopping directory affording a quick reference to usual requirements of a hotel guest strange to the locality of the hotel, in order to provide for the convenience of finding such places local to the hotel at which he stops, for the usual or occasional requirements of a traveler. In particular it serves in one device the double purpose, while still maintaining normally the device without increase of bulk or any other objectionable characteristics beyond what is normally incident to the form and arrangement of a hotel guest room key identification check or tag.

A particular embodiment of our invention is shown in a form which will now be more particularly described, as shown in accompanying drawings, in which:

Fig. I is one form of the improved key tag link and key.

Fig. II is a side elevation.

Fig. III is a top view.

Fig. IV is a bottom view.

Fig. V is a view with the directory compact partially opened for consultation.

Fig. VI is a modified form of tag with stub tag, link and key.

Fig. VII is a section showing the stub tag and compact assembly connection.

In the particular form shown in the preferred construction, 1 is the tag cover of stiff material adapted to receive the identification imprint, such as shown, 2 is the back cover of size and shape registering with the front cover 1, 3, 3^a, 3^b, etc., are the plurality of thin leaves 45 of the compact being of the same shape and registering in form and size with the covers, and adapted to receive printing such as the index on sheet 3, and directory or advertising on sheets 3^a, 3^b, etc.

50 The covers and compact are held together

with a pivotal connection 4, such as an eyelet which accommodates one end of a link 5 which is split with an oblique joint 6, which provides for the attachment of the key 7, allowing freedom of articulation for the manipulation of the key, and providing for the removal from the key for replacement of a new tag and compact at times when desired.

At the opposite end of the tag from the pivot 4, a latch or lock 8 is secured by a pivot 9 to the top cover which provides for oscillation to an extent that permits the end 10 of the latch to slide over the front and back covers with the directory sheets between them, and is so fashioned that a slight inward bulge 11 in the metal of the clasp registers with a slight depression 12 formed on the top surface of the front cover, and a similar locking means engages a suitable depression 12^a or equivalent locking means on the outer surface of the back cover. This latch is preferably so formed as to have no excrescences that would cause it to be pulled accidentally when carried in the pocket and subject to normal use, but is preferably made with flush connections wherever necessary to serve the purpose of insuring a smooth outside configuration to the tag when the tag is in normal locked position. The inner bulge 11 provides a recess on the outer surface of the latch, 80 which is a means affording sufficient finger-hold so as to provide for voluntary opening of the latch when desired.

The thin leaves of the compact 3, 3^a, 3^b, etc., are shown in Fig. V, in which an index leaf 3 is the top of the compact having in the particular form illustrated, a list of the different classes of stores which a hotel guest strange to a city might wish to find without delay. This serves as a directory so long as he occupies the hotel and has his hotel key with him,—and thus combines in the one item which a guest invariably carries about during his stay in a strange town, the added data and information which he might at any moment desire,—without carrying with him anything in addition, or without delay and trouble in turning to others for consultation or inquiry.

Under the index sheet and corresponding to the number of class of stores is a reference

sheet with the same number giving a selection of the stores of that class, such as illustrated as 3^d, which enables him to pick the most convenient at the time of reference to his hotel key tag directory, or to select one meeting his then needs, and with the assurance that the hotel key would naturally refer guests to the selected number of proper and most available shops or places.

- 10 In the form shown in Figs. VI and VII, the key link and tag are combined in a way that such a stub tag 14 is permanently attached by the link 15 to the key 7, and this stub tag is so arranged that a compact consisting of a cover and the plurality of directory sheets 16, 16^a, etc., may be separately formed with the latch 8^a and with registering holes or with an eyelet to receive the pivot 17, and may be slid into a groove 18 and locked by any suitable means 19,—thus forming the complete identification tag and index. In this form separate sets of index cards, with covers prepared, may be readily provided from time to time as the conditions of the directory and 25 advertising embodied therein change, and quick replacement of such directories may be made, while still leaving firmly attached to the key a stub tag with the hotel identification, in the event that by accident, or otherwise, a guest should remove the index and 30 directory.

It will thus be seen that in the various forms of our invention we provide a tag which in its normal closed form, may be identically 35 the same in shape as the present tags used on hotel keys for identification, and of a size that is used to prevent mislaying or loss of keys. With this is embodied the additional and very useful element of a ready reference 40 directory or index for such particular information as is always desired by a hotel guest. Providing thus the double purpose in a single article, without added size or any inconvenience in handling, affords a 45 means of serving added utility, convenience and economy. This provides the added advantage of affording the opportunity of uniformity in the provision of tags, and therefore the ultimate economy to the hotel interests 50 besides the advantages as heretofore set forth.

Various forms and details of construction may be used for efficiency and economy or other requisites of the device, but as an article 55 of manufacture it may be introduced in uniform size and shape, or may be made in numerous different forms and sizes to suit the desires of different users.

What we claim and desire to secure by 60 Letters Patent is:

1. A hotel key tag comprising a stiff member forming an identification cover, a plurality of thin sheets of similar shape to the cover and having on one side a series of index offsets, a stiff side wall integral with the cover

forming a flat abutment for all of the thin sheets on the opposite side from the index offsets, a stiff back member conforming in size to the cover, means attached to the cover for locking the back, cover and intermediate 70 thin sheets when in register in fixed position, and means for securing the cover and the compact thin leaves together permitting articulation of the same, whereby upon releasing of the locking means visibility of any 75 of the leaves is permitted for ready reference.

2. An identification tag, comprising a tag-plate or cover adapted to carry the permanent identification marking and including 80 means for securing the same to a key or the like, a substantially right-angled offset along one edge of the plate and a multiplicity of relatively thin leaves or cards of substantially the same shape of the cover-plate, and 85 means interconnecting the leaves and the plate whereby the leaves abut the offset from the one edge of the plate when the leaves are in register with the plate, said pivotal means permitting the swinging or opening 90 of the leaves to a position whereby substantially the whole face of each leaf provides a field for recording guide or like reference information.

3. A key identification and guide-tag, comprising a stiff permanent identification cover or plate, a substantially right-angled offset along one edge of the cover, a plurality of leaves adapted to abut against said offset and having substantially the same shape as the 100 cover, a pivotal connection between the cover and the leaves, and an offset at one end of the cover and leaves for said pivotal connection and in proximity to the lateral abutment or side offset of the cover.

4. A key-tag comprising a rigid cover-member, a pack of leaves, a substantially right-angled turned edge on one side of said cover projecting from the inner face of the cover an extent equal to the thickness of the pack of leaves, means for pivotally attaching to said cover said plurality of leaves, a means for voluntarily locking said pack of leaves rigidly to said cover member.

5. A tag for a key for hotel use or the like, comprising a multiplicity of like shaped cards adapted to be stacked together and each adapted to carry on substantially its entire face a directory or guide record visible when exposed, stiff front and back covers carrying a pivotal connection for a key-ring and cooperating to hold the cards in permanent relation and permit the swiveling of the cards into register with the covers and out of register with the covers for visibility, and means for holding all cards and covers in registered compact alignment, said means being substantially flush with the edge of the covers when the tag is consolidated by locking the covers with the cards in registration.

6. A hotel key tag constituting a portable combined identification tag and director, having a multiplicity of directory cards and a stiff tag cover of the same size and shape
5 pivotally connected for consolidation as a rigid key tag and readily displaceable for ready reference to any one of the multiple directory sheets or cards and means attached to the cover to voluntarily lock together the
10 cards and cover as a unit tag structure, and for voluntarily releasing the cards to permit their free displacement from position of registration with the cover.

In testimony whereof, we have signed our
15 names to this application this 20th day of September, 1929.

LEONARD A. BIGGS.
SAMUEL R. GOLDSTEIN.
